Primary Examiner — Susan E Krakower*Assistant Examiner* — Michael Maharajh(57) **CLAIM**

We claim the ornamental design for a receptacle, as shown and described.

DESCRIPTION

FIG. 1 is a front top perspective view of a receptacle showing our new design;

FIG. 2 is a rear top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a front bottom perspective view thereof.

The evenly spaced broken lines shown in the figures are for the purpose of illustrating portions of the receptacle and form no part of the claimed design.
